(57) **CLAIM**

The ornamental design for a drum claw hook, as shown and described.

DESCRIPTION

1. Drum claw hook

1.1 : Perspective

1.2 : Front

1.3 : Back

1.4 : Left

1.5 : Right

1.6 : Top

1.7 : Bottom

The dashed broken lines illustrate portions of the drum claw hook and form no part of the claimed design; the dot-dashed lines in figs. 1.1, 1.2 and 1.4 to 1.7, define boundaries of the claimed design and form no part thereof.
